United States Patent Office

Des. 183,014
Patented June 10, 1958

183,014

BOOKKEEPING MACHINE OR THE LIKE

Jiri M. Nessel, Los Angeles, Calif., assignor to Clary Corporation, San Gabriel, Calif., a corporation of California

Application November 8, 1957, Serial No. 48,394

Term of patent 14 years

(Cl. D64—11)

Des. 183,014

PAGE 2

Fig. 1 is a side perspective view of a bookkeeping machine showing my new design;

Fig. 2 is a top plan view; and

Fig. 3 is a side elevational view thereof, the side opposite thereto being substantially similar in appearance.

The essential features of my design reside in the parts shown in full lines on the drawing.

I claim:

The ornamental design for a bookkeeping machine or the like, substantially as shown and described.
